(57) **CLAIM**

The ornamental design for a note and clip, as shown and described.

DESCRIPTION

FIG. 1 shows a perspective view of a first embodiment of a design of a note and clip.
FIG. 2 shows a right-side view of FIG. 1. A left-side view is a mirror image of the right-side view.
FIG. 3 shows another perspective view of FIG. 1.
FIG. 4 shows a front view of FIG. 1. A back view is a mirror image of the front view.
FIG. 5 shows the right-side view of FIG. 1. A left-side view is a mirror image of the right-side view.
FIG. 6 shows a back view of FIG. 1. The front view is a mirror image of the back view.
FIG. 7 shows a top view of FIG. 1.
FIG. 8 shows a bottom view of FIG. 1.
FIG. 9 shows a perspective view of a second embodiment of a design of a note and clip.
FIG. 10 shows a right-side view of FIG. 9. A left-side view is a mirror image of the right-side view.
FIG. 11 shows another perspective view of FIG. 9.
FIG. 12 shows a front view of FIG. 9. A back view is a mirror image of the front view.
FIG. 13 shows the right-side view of FIG. 9. A left-side view is a mirror image of the right-side view.
FIG. 14 shows a back view of FIG. 9. A front view is a mirror image of the back view.
FIG. 15 shows a top view of FIG. 9.
FIG. 16 shows a bottom view of FIG. 9.
FIG. 17 shows a perspective view of a third embodiment of a design of a note and clip.
FIG. 18 shows a right-side view of FIG. 17. A left-side view is a mirror image of the right-side view.
FIG. 19 shows another perspective view of FIG. 17.
FIG. 20 shows a front view of FIG. 17. A back view of this embodiment is a mirror image of the front view.
FIG. 21 shows a right-side view of FIG. 17. A left-side view of this embodiment is a mirror image of the right-side view.
FIG. 22 shows a back view of FIG. 17. A front view of this embodiment is a mirror image of the back view.
FIG. 23 shows a top view of FIG. 17; and,
FIG. 24 shows a bottom view of FIG. 17.
The surfaces of the note are entirely unclaimed except for the edge lines that are shown as solid lines. The broken-line features in the figures are for illustrative purposes only and form no part of the claimed design.
